United States Patent Office

Des. 185,002
Patented Apr. 28, 1959

185,002

HEAD OF A PUTTER

Robert W. Hyde, Cincinnati, Ohio

Application November 18, 1957, Serial No. 48,507

Term of patent 3½ years

(Cl. D34—5)

The face of the putter not shown in substantially planar.

I claim:

The ornamental design for a head of a putter, substantially as shown and described.
